PAPER BOTTLE AND CONTAINER

Harold H. Felzer, Astoria, Long Island, N. Y.

Application June 13, 1940, Serial No. 340,296

3 Claims. (Cl. 229—4.5)

This invention relates to a new and useful improvement in paper bottles and containers, and, in particular, to a bottle made from heavy paper or light board stock having a body, which is square or rectangular in cross-section, a bottom integral therewith, and inset somewhat above the bottom edge, a neck projecting from the upper edge of the body, which gradually tapers and approaches a round cross-section which it acquires at its upper end, and which may be enveloped by an annular lip of a size adapted to receive any standard cap or closure such as that used for closure such as that used for closing glass milk bottles, for example.

Important features embodied in this invention are the strength and rigidity of the bottom, the stiffness of the neck and also the smoothness of its interior, which, although formed by pleating, presents a surface which is substantially as smooth and unbroken as that of a glass bottle, and the reinforcement of the vertical edges of the body by internal outstanding ribs, which co-operate with the bottom and the neck reinforcement to give the bottle extraordinary resistance to distortion or crushing, although it may be made from relatively light stock which ordinarily would respond without much resistance to even light pressure.

Since one of the important uses of this bottle is as a container for milk, the form selected for illustration in the drawings hereof and description herein is designed particularly for that service, so that standard filling and capping equipment, for which most dairies are now equipped, can be used without alteration. However, it will be understood that the invention is not limited to a bottle for this purpose or to the actual or relative dimensions shown.

In the drawings—

Figure 1 is a side elevation of a complete bottle embodying this invention;

Figure 2 is a side elevation of the same bottle, turned by 90° from the position shown in Figure 1;

Figure 3 is a top plan view of the same bottle;

Figure 4 is a bottom plan view of the same bottle;

Figure 5 is a vertical cross-section of the same bottle on the line 5—5 of Figure 3, viewed as indicated by the arrows;

Figure 6 is a diagonal vertical cross-section of the bottle on the line 6—6 of Figure 3 viewed as indicated by the arrows;

Figure 6A is a general view of the blank from which the bottle is made;

Figures 7-13 are illustrative of various steps in the manufacture of the bottle from the blank shown in Figure 6A; and

Figures 14 and 15 illustrate schematically a method by which the bottom when otherwise completed can be inset sufficiently above the bottom edge of the bottle to insure that the bottle will sit on its bottom edge rather than on the bottom proper.

10 Figure 6A shows the back or inside surface of the blank 1 from which the bottle is made. It consists of a piece of heavy paper or light board stock divided into four identical panels, 2, 3, 4 and 5, by vertical scores 6 impressed from the inside or back of the blank so that they form outwardly-projecting ribs at the vertical outer corners of the bottle.

Beginning at the point 7, which is the junction between the body and the neck of the bottle, 20 panels, 2, 3, 4 and 5 taper symmetrically to the top of the blank, the taper being such that when the bottle is formed, the edges 8 and 9 of adjacent panels will meet throughout their length. Beyond the outer edge of one of the outer panels (5, for example) is a flap 10 which, when the bottle is formed, overlaps the outer edge of the opposite panel 2, and is tightly secured thereto by a suitable adhesive.

The tapering neck parts of panels 2, 3, 4 and 5 and the corresponding neck part of flap 10 are formed by score lines 12 and 13 forming integral V-shaped pleating sections 11 through the center of which scorings 6 are extended to the top edge of the blank. Scorings 12 and 13 are impressed from the face or outside surface of the blank beginning at the points 7 which are in transverse alignment at the point where the bottle body shoulder is formed and from which the bottle neck formed by the tapering panel sections taper upward to the bottle mouth. Sections 11 project at an angle above the upper edges of the neck panels with the apex of each angle at a score line 6 so that when the bottle is formed, the upper edge of each pleat section 11 will be in alignment with the edges of the panels forming the bottle mouth and thereby form a level seat for the mouth lip or ring which is applied to firmly hold the pleats and to provide a seat for the bottle closure.

50 The base of the bottle will be at the line 14, Figure 6A, at which point the blank has a transverse scoring 15 impressed from the back or inside of the blank extending across the entire width of the panels 2—5 including flap 10. Below this line are formed five integral bottom

sections or panels 16, 17, 18, 19 and 20 defined by the longitudinal scorings 6. Panel 16 adjacent the body panel 2 is a square section adapted to extend over the entire bottom area, and panels 17, 18 and 19 are rectangular sections half the width of the bottom area, and panel 20 is the width of flap 10 and its length is equal to the width of sections 17-19. Bottom sections 17 and 19 are provided with diagonal scorings 21-22 and 23-24, respectively, impressed from the back or inside of the blank and extend from a mid-point on the edges of sections 17 and 19 to the corners at the junction of scorings 6 and 15 forming each of these sections into three triangular sections, indicated by reference numbers 17, 25 and 27 adjacent panel 3, and reference numbers 19, 26 and 28 adjacent panel 5.

The various surfaces of the bottom sections just described which form the bottom of the bottle, with the exception of those which constitute the inside and outside surfaces, should be coated with adhesive to stick them together so tightly as to make the bottom proof against leakage and also to give it the greatest possible strength and rigidity. A preferred distribution of adhesive on the inside and outside surfaces of the bottom sections, is indicated by the stippling in Figures 6A, 10, 11 and 12.

As shown in Figure 6A, bottom sections 18 and 20 have the adhesive on the under or outside, and section 16 has the adhesive partly covering the upper or inside. The clear surfaces of these sections when folded in become the upper layer or inner side of the bottom as seen in Figure 7, the rectangular section 18 becoming one-half of the inner bottom surface and the blank part of section 16 and section 20 becoming the other half of the inner bottom surface.

From this blank the bottle may be made as follows: The blank is first folded upon scorings 6, around a mandrel corresponding in size and shape to the inside of the bottle and flaps 10 and 20 are folded either inside or outside of the outer edge of panel 2 and securely attached thereto by adhesion. Preferably flaps 10 and 20 are secured to the inside of panel 2 since this produces the neatest appearance in the finished bottle and this method has been followed in the bottle shown in the drawings. The blank has now assumed the shape of an open-ended tube of square cross-section as shown in Figure 10.

The next step is preferably to form the bottom. This is done by folding section 18 inwardly on scoring 15, and the folding of section 18 inward draws triangular sections 25 and 26 of bottom sections 17 and 19, respectively, inward on scorings 22 and 23 as seen in Figure 11. Then section 16 is folded inward on scoring 15, drawing triangular sections 27 and 28 of bottom sections 17 and 19 inward on scorings 21 and 24 forming the two double-ply large triangular sections 17 and 19 as seen in Figure 12. These triangular sections 17 and 19 are then folded inward to form the outer layer of the multiply bottom as seen in Figure 13.

The final step with respect to the bottom is to recess it slightly so that the bottle will stand upon its lower edge or chimb and not on the bottle bottom. This may be done by the device schematically illustrated in Figures 14 and 15, which consists of a form 29 within which the body of the bottle will fit snugly, a mandrel 30, previously mentioned, fitting the inside of the body of the bottle and a die 31 having an end 32 smaller than the cross-sectional dimensions of the bottle

adjacent the bottom by approximately twice the thickness of the stock from which the bottle is made. By causing die 31 to approach the bottom of the bottle and causing mandrel 30 to recede a little, the reduced end 32 will force the bottom inwardly slightly, as shown in Figure 15, so that all layers of the bottom will lie above the bottom edge or chimb of the bottle. Since this causes the edges of the bottom sections adjacent transverse scoring 15 to fold upwardly, as shown in Figure 15, the extreme bottom edge of the bottle is provided with a reinforcement integral with the bottle body and bottom and when this reinforcement is firmly secured to the bottom edge of the bottle by adhesive, an extremely strong and rigid structure results. To this end it is desirable that adhesive be applied to a narrow strip both above and below the transverse scoring 15 all the way across the inside surface of the blank, as shown in Figure 6A.

The next step is to form the neck. This is done by bending the four tapering sections of panels 2-5 inwardly until the edges 8 and 9 of the adjacent tapering sections meet, as shown in Figure 8. This can be done by pleating sections 11 outwardly along scoring 6, 12 and 13, which is also shown in Figure 8. In this way a bottle neck having the shape and dimensions of the body shoulder is formed, but which gradually approaches a circular shape which it acquires at its upper end to form the bottle mouth. The interior surface of the neck is composed entirely of the tapering parts of the blank panels 2-5, the edges of which lie close together on the score lines 12-13 throughout their length so that the interior of the bottle is substantially smooth and unbroken and very similar to that of an ordinary glass bottle.

The next step is to fold the projecting pleats 11 shown in Figure 8 upon the neck panels, preferably towards each other, as shown in Figure 9, so that they lie flat in opposite pairs against the outside of the neck panels. Since these pleats are integral with the neck panels there is no possibility of leakage in this portion of the bottle. They also form extremely efficient reinforcing and stiffening ribs for the neck, and since they overlie the junction between adjacent edges of the neck panels and lie snugly against them, there are no recesses of any consequence into which liquid can pass. As a matter-of-fact, when the bottle is coated with paraffin or other coating material, the minute space between the edges of adjacent panels will be filled so that the interior of the bottle is substantially smooth and unbroken as heretofore mentioned.

The upper end of the neck may be finished off in any suitable way as by a ring 33, which is usually channel-shaped, so that it can be slipped down over both the inside and outside of the upper edge of the neck and secured thereto by contracting the ring from one or both sides in a manner which will insure that there will be no leakage as shown, for example, in Figures 5 and 6. Since this ring is usually applied before the bottle is coated any minute spaces which may remain as the result of the varying thickness of the neck will be filled.

Scorings 6 between the body panels 2-5 are impressed, as stated, from the back of the blank and should be rather deep so that beads are definitely formed upon the outside of the blank. These scorings when made in this way not only facilitate the folding of the body panels, but produce outstanding stiffening beads along the ver-

tical corners of the body of the bottle, as best indicated in Figures 3, 7 and 9, at 6a.

Thus the bottle has a heavy rigid recessed multiply bottom with a two-ply chimb, a body portion with stiffened corners and a neck portion also provided with stiffening folds, the effect of all of which, particularly when the ring 33 is added, is to produce a bottle made from relatively light stock which is very resistant to crushing or distortion from either the outside or the inside. It is obvious that the manufacture of the bottle requires relatively few and simple operations so that it possesses the additional extremely important characteristics of cheapness and the possibility of manufacture at high speed.

The adhesive employed in manufacturing this bottle may be a wet adhesive applied before the blank is folded, or a plastic adhesive, the properties of which are realized by the subsequent application of heat and pressure. Paraffin and many other coating materials should be considered as adhesives as the term is used herein, since they have incidental adhesive properties which not infrequently are adequate so that no other adhesive need be used.

I claim:

1. A blank for paper bottles formed from an integral sheet and designed to provide three series of four panels each defined by scorings, one series of panels comprising four laterally adjacent longitudinally extending panels designed to form a bottle body the lower part of which is rectangular in cross-section, the lower part of each of said panels being rectangular in shape and the upper part of trapezium shape with the longitudinal sides slanting equally toward each other, a second series of panels comprising four V-shaped sections adjacent the trapezium shaped sections, said adjacent sections being designed to form a tapering upper body part, a third series of panels comprising four panels adjacent to and in vertical alignment with the body panels and

designed to form the bottle bottom, one of said panels adjacent an end body panel being rectangular in shape and equal in area to the cross-sectional area of the bottle body, and each of the other three of said bottom panels being rectangular in shape and one-half the cross-sectional area of the bottle body, and a relatively narrow longitudinal sealing section adjacent the other end body panel.

- 10 2. A paper bottle having a rectangular body section, a tapering neck section, circular mouth, and multi-ply bottom, formed from a single integral sheet of paper having four panels spaced by longitudinal score lines, a relatively narrow longitudinal section for joining the sheet into a rectangular tube, the mid-section of the panels forming the body, the upper sections of the panels tapering symmetrically toward the mouth and spaced by oblique score lines meeting at 15 the body shoulder to form the tapering neck, V-shaped sections between the neck sections and each divided into equal angular sections by the longitudinal score lines and each folded on said score lines against the neck sections, and a bottom section projecting from the body section 20 and spaced by said longitudinal score lines into four rectangular panels of equal width, one of said panels being equal in area and shape to the cross-section of the body, the three adjacent panels being each approximately one-half the 25 length of the first named bottom panel, and two of the bottom panels having a pair of diagonal score lines, and said bottom panels being folded inward so that the larger panel will lie intermediate the smaller unscored panel and the pair of diagonally folded panels on the exterior of the 30 bottom.

- 35 3. A paper bottle formed as specified in claim 2, having the bottom recessed to form a chimb by pressing the bottom panels inward after being folded into position.

HAROLD H. PELZER.
